UNITED STATES PATENT OFFICE.

WILLIAM A. DURST, OF AUGUSTA, GEORGIA.

TANK.

Application filed February 27, 1925. Serial No. 12,098.

To all whom it may concern:

Be it known that I, WILLIAM A. DURST, a citizen of the United States, residing at Augusta, in the county of Richmond and State of Georgia, have invented a new and useful Tank, of which the following is a specification.

The present invention relates to a valve construction and valve operating mechanism especially designed for use in connection with closet bowls, the primary object of the invention being to provide a simple and economical means for automatically controlling the valve in the tank, associated therewith.

Another object of the invention is to provide a valve controlling mechanism eliminating the use of the usual floats, springs and washers, thereby insuring against leakage and other common troubles.

A still further object of the invention is to provide a valve controlling mechanism wherein the tank which supplies the water to the bowl will normally be emptied, thereby insuring against leakage.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a longitudinal sectional view through a tank and valve mechanism constructed in accordance with the invention.

Figure 2 is a longitudinal sectional view through a tank and valve mechanism, the valve mechanism being shown as in a position to release the water in the tank.

Figure 3 is a sectional view taken on line 45 3-3 of Figure 1.

Figure 4 is an elevational view of the main valve member.

Figure 5 is a sectional view taken on line 5-5 of Figure 1.

Figure 6 is a sectional view taken on line 6-6 of Figure 1.

Figure 7 is a sectional view taken on line 7-7 of Figure 1.

Figure 8 is an elevational view of one of 55 the valve members, illustrating the manner

of securing the valve members to their supporting rod.

Referring to the drawings in detail, the reference character 5 indicates the usual closet bowl, which is supplied with the usual seat portion 6 that is hingedly connected to the bowl, at 7. Extending rearwardly from the seat portion 6 are the spaced arms 8, which are formed with curved end portions 9 adapted to engage the laterally extending pins 10 formed on the movable collar 11 that operates on the pipe section 12. Secured to the pipe section 12 by the set screws 13' is a collar 13 that is disposed directly above the collar 11 and held in spaced relation therewith by means of the coiled spring 14 that cushions the contact between the valve 22 and its seat 21. The upper end of the pipe section 12 is flared as at 15 to accommodate the lower end of the pipe section 16 which is flared at its upper end to receive the lower end of the enlarged pipe section 17 that has its upper end mounted on the pipe section 18 that extends into the tank 19.

The pipe section 17 moves over the pipe section 18 there being provided a coiled spring 20 positioned on the pipe section 18 and arranged between the bottom of the tank 19 and upper end of the pipe section 17 to push the entire pipe sections downward and raise the seat 6 after the toilet has been used. Positioned within the pipe section 18 is a valve seat (brass bushing) 21 against which the valve member 22 moves, the valve member 22 being provided with guides 23 to insure the true vertical movement of valve 22 against its seat. Positioned within the pipe section 17 and secured thereto, is a rod 24 that also extends through the valve member 22 to cause the valve member to move upwardly or downwardly with the movement of the pipe section 17 to close the lower end of the pipe section 18 to prevent fluid from passing from the tank.

The reference character 25 indicates a valve rod which is connected with the valve member 22, the upper end of the valve rod being provided with a head 26 adapted to engage the member 27 disposed at the lower end of the valve rod 28. At the upper end of the valve rod 28 is secured the valve member 29 that is formed with an opening to accommodate the reduced threaded portion 30 of the rod 28 so that the valve member 29

may be removed if necessary. The water supply pipe is indicated at 31 and extends into the tank 19. At the end of the pipe 31, inside the tank, is secured the valve housing 32. This valve housing 32 is $1\frac{1}{2}$ inches long and is reamed out in such a manner as to leave a valve seat at the lower end, against which the valve 29 moves to cut off the passage of water to the tank 19, as shown in Figure 2 of the drawings. After the valve 29 has been inserted in housing 32, the housing is screwed on the end of pipe 31.

From the foregoing it will be obvious that as weight is applied to the seat 6, the collar 11 will move upwardly against the tension of the spring 14 moving the various pipe sections supported above the collar 11, upwardly, and moving the valve member 22 to a position to cut off the passage of water from the tank 19. Simultaneously with the upward movement of the valve 22, the head 26 engages the member 27 which moves the rod 28 and valve member 29 supported at the upper end thereof to a position as shown by Figure 1 of the drawings, allowing water to pass into the tank 19 to fill the tank. When the weight on the seat is removed it is obvious that the water pressure within the tank 19 will force the valve member 22 from its seat, releasing the water in the tank 19 which passes into the bowl 5. With the downward movement of the valve 22 the valve member 29 takes a position as shown by Figure 2 of the drawings, cutting off the passage of water to the tank 19, and leaving the tank empty, until weight is again applied to the seat section to operate the valve members as described.

I claim:

- 40 1. In a device of the character described, a tank, a bowl disposed under the tank, movable pipe sections providing communication between the bowl and tank, a hinged cover for the bowl and having connection with the movable pipe to move the pipe when the cover is moved, and valve members controlled by the movement of the pipe for controlling the passage of fluid to and from the tank.
- 45 2. In a device of the character described, a tank, a bowl under the tank, a vertically movable pipe establishing communication

between the tank and bowl, a cover for the bowl, means for connecting the cover and pipe to transmit movement from the cover to the pipe, a pipe extending into the pipe for supplying water thereto, a valve in the last mentioned pipe, a valve for controlling the passage of water from the tank, and said valves adapted to be operated by the movement of the cover and first mentioned pipe.

3. In a device of the character described, a tank, a bowl under the tank, a pipe for establishing communication between the pipe and bowl, a supply pipe extending into the tank, valves for controlling the passage of fluid from the tank, and from the supply pipe, a cover for the bowl, and means for transmitting movement of the cover to the first mentioned pipe for operating the valves.

4. In a device of the character described, a tank, a bowl under the tank, a vertically movable pipe establishing communication between the tank and bowl, a valve member for controlling the passage of fluid from the tank, a rod extending through the tank and having connection with the valve member to move the valve member with the pipe, a cover for the bowl, and means for transmitting movement of the cover to the pipe to operate the valve.

5. In a device of the character described, a tank, a bowl under the tank, a vertically movable pipe establishing communication between the tank and bowl, a cover for the bowl, means for transmitting movement of the cover to the pipe, a valve controlled by the movement of the pipe to control the passage of fluid from the tank, a supply pipe extending into the tank, a valve member within the supply pipe and adapted to be operated by the first mentioned valve member to release water in the pipe to fill the tank as the first mentioned valve member is seated.

In testimony that I claim the foregoing as my own, I have hereto affixed my signature in the presence of two witnesses.

WILLIAM A. DURST.
